to Railroad Accessories Corporation, New York,
N. Y., a corporation of New York

Application July 2, 1941, Serial No. 400,782

2 Claims. (Cl. 173—269)

This invention relates to wire terminals or eyelets.

A primary object of this invention is the production of a device of the class specified which will exhibit the desired characteristics of known wire terminals or eyelets and in addition will provide means for accurately positioning the end of the insulation of a bared end insulating wire.

A further object of the invention is to provide a device of the type specified with the features as hereinbefore specified and in addition affording a much stronger structure in that portion wherein known eyelets are most weak.

Other objects and advantages will appear as the description of the particular physical embodiment selected to illustrate the invention progresses, and the novel features will be particularly pointed out in the appended claims.

In describing the invention in detail, reference will be had to the accompanying drawing and the several views thereon, in which similar characters of reference designate like parts throughout the several views, and in which:

Figure 1 is a top plan view of an eyelet of applicants' invention with the bared end of an insulated electric conductor secured therein; Fig. 2 is an illustration of the device of Fig. 1 as applied to a well known type of electric conducting binding post; Fig. 3 is a cross-sectional view of the device as shown by Fig. 1 on the plane indicated by the line III—III of Fig. 1, viewed in the direction of the arrows at the ends of the line; Fig. 4 is a cross-sectional view of the device as shown by Fig. 3 on the plane indicated by the line IV—IV, viewed in the direction of the arrows at the ends of the line; Fig. 5 is a cross-sectional view of the device as shown by Fig. 1 on the plane indicated by the line V—V of Fig. 1, viewed in the direction of the arrows at the ends of the line; Fig. 6 is a side elevational view of the device as shown by Fig. 1 before it has been applied to the end of an insulated conductor but with a part broken away to more clearly show the internal construction; Fig. 7 is a right hand end view of the device as shown by Fig. 6; Fig. 8 is a left hand end view of the device as shown by Fig. 1 but showing by dotted lines certain parts before compression; Fig. 9 is a perspective view of the device as shown by Fig. 6.

Wire terminals or eyelets are old and well known in the electrical art.

Wire eyelets of the general form of applicants' eyelet are old and well known in the electrical art.

Applicants' eyelet is an improvement of known eyelet arrived at by observation of the action of known eyelets in use, and acquaintance with the defects of known eyelets and conception of a means for overcoming the more prominent defects.

The eyelet of applicants' invention is made of

a single piece of material and may be designated as a whole as shown in Fig. 9, by E.

The eyelet of applicants' invention comprises a single body of conducting material, preferably copper or brass and preferably tinned.

The eyelet includes a substantially circular body 1, formed with a substantially semi-circular channel 2. At one end of the channel 2 there is a throat 3. The throat 3 is bent into substantially a right angle providing a shoulder 4.

Extending beyond the shoulder 4 is substantially a U member 5, the curve 6 of which terminates at the shoulder and the legs of which extend along the shoulder and substantially beyond the shoulder in a direction at a right angle to the general plane of the channel.

It has been found in practice that known types of wire terminals are very weak in the throat corresponding to the portion 3 of applicants' device. In known types, the throat 3 is substantially a thin strip of sheet metal. In applicants' device, the throat 3 is substantially a sheet of thin metal, but in applicants' case, reliance is not placed upon the strength of the sheet metal of the throat 3 to prevent breakage at that point because on each of opposite sides of the throat a somewhat right angle wall extends from the throat terminating at one end 7 as shown by Fig. 6 somewhat adjacent to and merging with a leg as 8 of the U and then proceeding by a shallow curve to about one quarter of the way around the body 1, as at about the point 9, where it merges with the outer edge of the channel. These resistor walls on each of opposite sides of the throat provide what is practically a resistor to bending of the throat in a plane substantially at a right angle to the general plane of the channel. In practice, it has been found that this additional feature of construction over known wire eyelets is of immense advantage and of great efficiency in that it greatly prolongs the life of the terminal in that it prevents breaking of the terminal through the throat 3.

Another defect of known terminals has arisen from the fact that one or more strands of the stranded conductor when placed within the channel 2 would escape therefrom by reason of the fact that the means for holding the strands in the channel met the free edge of the channel directly.

In applicants' construction, there is provided an annulus 10 around the inner edge of the channel and this annulus is provided at its free edge with a flange 11. This annulus 10 and flange 11 are adapted to be compressed and surround a stranded conductor, as best shown in Fig. 5, but in applicants' construction, the edge 12 of the annulus 10 passes beyond the free edge 13 of the channel and thereby quite insures against any

single strand of the conductor working out from beneath the flange and beyond the free edge 13 of the channel to perhaps touch an adjacent conducting binding post or terminal and so cause an undesired circuit to be formed.

In practice, an insulated conductor, as 14, is bared of its insulation for a relatively short distance at one end and the strands thereof are divided into substantially two equal portions. Then the insulating material is laid into the curve 6 of the U with the end thereof abutting the shoulder 4 thereby accurately positioning it. After being so positioned, the legs of the U 5 are wrapped about the insulating material and squeezed into place, as best shown in Fig. 4, forming substantially an annulus which securely holds the conductor and positions it properly against the shoulder 4 so that it may not ride up on the throat 3 and cause defects. The divided ends of the conductor are passed, one around one side and the other around the other side and in the channel 2, as best shown in Fig. 1. The ends of the two portions are generally twisted together as at 15. The annulus 10 with the flange 11 is then squeezed down into place as shown in Figure 8 by full lines. As shown by Fig. 5, when this annulus has been so squeezed down the end of the flange 12 and the free end 13 of the channel pass one another but do not meet face to face. After the annulus 10 and flange 11 are squeezed down into place, if there is any surplus wire extending at the point 15 that is not wanted, it may be cut off.

In order to prevent any interference with the squeezing down of the flange 11 at the point where the ends 15 come together, notches, one 16, in the flange 11 and the other, 17, in the body 4, are formed to receive the bared ends of the conductor in such a way that they will not interfere with the squeezing down of the annulus 10 and flange 11.

The electrical conductor with its end provided with a terminal as described may then be placed over a binding post as 18 and securely held down thereon by a washer as 19 and a nut as 20.

Applicants have further provided against any interference with the squeezing down of the annulus 10 and flange 11 by terminating the annulus and flange at a point adjacent the throat 3. This termination is such that it would appear as though the annulus and flange have been cut away along a plane at a right angle to the general plane of the body, passing through a point just within the inner circle of the channel adjacent the throat, that is, on a plane passed through line 21 at a right angle to the sheet upon which the drawing is made. By cutting the annulus and flange along the plane designated, sharp points have been avoided at the points 22 and 23 which in the past have been found to be troublesome in those cases where the flange, such as 11, has been cut off on what might be considered a radial line from the center of the body 4.

Although we have particularly described one particular physical embodiment of our invention, and explained the operation, construction and principle thereof, nevertheless, we desire to have it understood that the form selected is merely illustrative, but does not exhaust the possible physical embodiment of the idea of means underlying our invention.

What we claim as new and desire to secure by Letters Patent of the United States, is:

1. A single piece eyelet connector for a conducting wire, comprising in combination: an electrical conducting body of general circular outline formed with a substantially semi-circular channel, a throat projecting radially therefrom, a U formed in extension of the throat, said throat on each side provided with a right angle wall extending from adjacent and merging with the extreme free end of a leg of the U in a shallow curve only about the distance of the throat around to an outer edge of and merging with the channel serving as a resistor to bending of the throat in a plane substantially at a right angle to the general plane of the channel and means for securing an electrical conducting wire in the said channel, the legs of said U being adapted to be wrapped from opposite sides about the insulation of a conductor forming substantially a closely fitting annulus thereabout.
2. A single piece eyelet connector for an insulation cover stranded electrical conducting wire, having the insulation removed for a relatively short distance at the extreme end, comprising, in combination: an electrical conducting body of general circular outline formed with a substantially semi-circular channel, a throat projecting radially therefrom, said throat including a right angle bend therein forming a shoulder adapted to abut the end of insulation of a bared conductor, said throat beyond the shoulder being formed into a U, the curve of which terminates at the shoulder and the legs of which extend along and substantially beyond the shoulder in a direction at a right angle to the general plane of the channel, said legs adapted to be wrapped from opposite sides about the insulation of a conductor forming substantially a closely fitting annulus thereabout, said throat on each side provided with a somewhat right angle wall extending from adjacent and merging with the extreme free end of a leg of the U in a shallow curve about the distance of the throat around to an outer edge of and merging with the channel serving as a resistor to bending of the throat in a plane substantially at a right angle to the general plane of the channel, said channel formed on its inner edge with an annulus extending at a right angle to the general plane of the channel, said annulus provided with a flange at its free end, said flange and annulus being continuous except for a portion adjacent the throat end of the channel where the flange and annulus are formed as though severed along a plane at a right angle to the general plane of the channel, said plane being positioned just forward of the inner surface of the channel adjacent the throat, said flange and channel at a point most remote from the throat being formed each with a notch adapted to allow protrusion of the ends of a conductor lying in the channel, said annulus and flange adapted to be squeezed down upon the end of a conductor divided and one portion passing around one side of the channel and the other portion around the other side and when entirely squeezed down having the edge of the flange lying entirely within the channel and its edge below the free edge of the channel.
